By Hull, Brock West, Atty's.

UNITED STATES PATENT OFFICE.

GEORGE T. WOODIN, OF NEWPORT, NEW YORK, ASSIGNOR OF ONE-HALF TO WILLIAM S. THORPE, OF LAKESIDE, OHIO.

MULTIPLE-FUSE PLUG.

Application filed July 30, 1921. Serial No. 488,520.

To all whom it may concern:

Be it known that I, GEORGE T. WOODIN, a citizen of the United States, residing at Newport, in the county of Herkimer and State of New York, have invented a certain new and useful Improvement in Multiple-Fuse Plugs, of which the following is a full, clear, and exact description, reference being had to the accompanying drawings.

This invention relates to multiple fuse plugs and has for its general object to provide a plug which shall combine efficiency with convenience of operation, simplicity and compactness of construction, and economy of production. I accomplish the foregoing objects, and other and more limited objects which will appear hereinafter, in and through the construction and arrangement of parts shown in the drawing forming a part hereof, wherein Fig. 1 represents a central longitudinal sectional view through a multiple fuse plug embodying my invention, the central contact, some of the parts connected thereto, and the fuses being shown in elevation; Fig. 2 a plan view of the base, corresponding substantially to the line 2—2 of Fig. 1; Fig. 3 a bottom plan view of the cap, corresponding substantially to the line 3—3 of Fig. 1; Fig. 4 a bottom plan view of the magazine part of the base, corresponding substantially to the line 4—4 of Fig. 1; Fig. 5 a detail in section corresponding to the line 5—5 of Fig. 3; and Fig. 6 an enlarged sectional detail showing the manner of supporting the contact arm from the cap and of establishing contact between said arm and the central contact.

Describing the various parts by reference characters, 1 denotes the upper magazine member and 2 the lower socket-connection member of a base. The member 2 is provided with the usual shell plug contact 3 which is adapted to fit a threaded socket shell contact (not shown). The upper end of the sheet metal of which the contact 3 is composed is flanged inwardly above a flat seat 2^a on top of the member 2, the flange constituting an annular contact surface 4.

The upper member 1 of the base is cylindrical in shape and is provided with a plurality of bores 5 located within and near the peripheral portion thereof. Six such bores are shown, spaced equidistantly apart and

equidistantly from the center or axis of the said member. 6 denotes an annular contact plate secured in any suitable manner to the bottom of the member 1 and extending beneath and closing the bottoms of the bores 5. The inner edge 6^a of this plate rests upon and forms an electrical contact within the annular contact surface 4. The member 2 is provided with a central recess 2^b in the top thereof and the member 1 with a corresponding central projection 1^b adapted to fit within the said recess, the members being secured together to form a unitary base by means of the central contact 7, which is provided at its lower end with a head 8 adapted to engage the lower end of the member 2. This contact extends upwardly through central bores in both of said members, indicated at 1^c and 2^c, and is provided within a recess 9 in the upper end of the member 1 with a nut 10 which serves to draw and hold the members 1 and 2 rigidly together.

Mounted within the bores or chambers 5 are the fuses, each fuse being of the cartridge type and consisting of an ordinary fuse wire (not shown) having its ends in electrical contact with the opposite metallic ends 11^a of a casing 11. In order to insure an efficient contact between the lower ends of the casings 11 and the plate 6, the latter is embossed upwardly beneath each such container, as indicated at 6^b.

Rotatably mounted upon the base and carrying a contact arm electrically connected with the contact 7 is a rotatable cap 13. The upper peripheral portion of this cap is preferably knurled, as indicated at 13^a, the cap being provided with a skirt 13^b depending from the body thereof and overlapping the upper end of the member 1. The cap is provided with a central bore 13^c having annular extensions 13^d and 13^e at the top and bottom thereof, respectively. Mounted in the annular extension 13^e is a sheet metal hub 14 carrying a contact arm 15. This arm is downwardly convex in cross section, as will appear from Figs. 5 and 6, whereby its lower surface tends to lie below the tops of the fuse casings, but the arm is enabled to ride up on top of the said casings as it is rotated by the cap. The hub 15 is clamped to the cap by means of a sleeve 16 having a head 17 at the lower end thereof adapted to engage the hub, the said

sleeve fitting within the bore 13^a and being internally threaded. This sleeve is secured in place by means of a second sleeve 17 threaded thereinto and having a head 18 adapted to fit within the recess 13^a. The sleeve 17 is threaded upon the contact 7, which can turn freely within the bore 2^c.

With the parts constructed and arranged as described, the operation will be readily understood. The base is screwed into its proper socket, with the arm 15 pressing downwardly upon the top of a casing 11 whereby, when a switch is closed at the proper place, a circuit will be established through the shell plug contact 3, plate 6, appropriate fuse in the casing 11, arm 15, members 16 and 17, and central contact 7. Should the particular fuse wire in use burn out, it is necessary only to turn the cap 13 sixty degrees, thereby bringing the contact arm 15 into engagement with the top of another fuse casing, whereupon the circuit will again be established through the fuse plug. The shape of the arm 15 will enable the operator to determine by the sense of feeling when the said arm has been moved a sufficient distance to engage the top of a fuse casing. Furthermore, the member 1 and the skirt 13^b will in practice preferably be provided with suitable indications adapted to register when the contact plate 15 is in operative relation to each of the fuse casings. The top of the cap 13 will also be provided with an arrow indicating the direction of rotation, thereby to prevent moving the arm 15 above and in engagement with the casing of a burned-out fuse.

When all of the fuses have been burned

out, the cap may be easily removed and new cartridge fuses inserted into the chambers 5. 40

Having thus described my invention, what I claim is:

1. In a device of the character described, the combination of a base having a central contact and a shell plug contact, an annular 45 plate in electrical engagement with one of said contacts, a magazine member having chambers the lower ends whereof are crossed by said plate, the said plate being embossed upwardly in each of said chambers, a fuse 50 casing in each chamber adapted to engage the embossed portions of the plate at their lower ends respectively, and an arm in electrical engagement with the other of said contacts and adapted by its rotation to engage 55 the upper ends of the said casings successively.

2. A device of the character described comprising a shell plug contact member and a magazine member, a central contact member uniting the first two members, fuse casings in the magazine member and grouped about the central contact member and in electrical contact with the shell plug contact, a contact arm cooperating with said 60 fuse casings, and having a central collar or hub, a rotatable cap having a central opening registering with the opening in said hub or collar, a sleeve mounted in the bore of said cap and having a head adapted 65 to engage the hub or collar, and a sleeve threaded into the first mentioned sleeve and to the central contact.

In testimony whereof, I hereunto affix my signature.

GEORGE T. WOODIN.
